UNITED STATES PATENT OFFICE

JOSEPH BERTRAM, OF CINCINNATI, OHIO

SHOE

Application filed June 20, 1927. Serial No. 199,886.

This invention relates to shoe shanks and is disclosed in relation to a lady's welt shoe.

One object of this invention is to provide a staunch and stable shank structure for a shoe.

Another object of this invention is to provide a staunch and stable shank structure for a shoe, said shoe adapted to be fabricated otherwise according to conventional commercial processes and without unusual machinery.

Another object of the invention is to provide a reenforced sole for a shoe, said sole constructed to provide a stiff shank portion for the shoe.

Other objects and certain advantages of the invention will be more fully set forth in the description of the accompanying drawings, forming a part of this specification, in which:

Figure 1 is a side elevation of a shoe with a portion of the side thereof broken away to disclose the shoe sole layers in section at the shank portion of the shoe.

Figure 2 is a sectional view taken on line 2—2, Figure 1, further detailing the fabrication of the shank portion of the shoe.

Figure 3 is a bottom view of the improved sole with a portion of the sole broken away to disclose a shank stiffener disposed therein.

Figure 4 is a sectional view taken on line 4—4, Figure 3, detailing a sleeve arrangement embodied in the sole.

Figure 5 is a sectional view taken on line 5—5, Figure 4, showing the shank piece in section and its relation to lines of stitching disposed at each side thereof.

A welt shoe conventionally comprises an upper 1 joined to an insole 2 to which is secured an outsole 3 by means of welt 4, stitching holding the welt to the insole and the outsole to the welt, and a heel 5 which is nailed at the rear end of the shoe.

According to this invention I modify one element of this combination, in this instance, the insole, by providing an insole (of the Gem type as disclosed) having a rear portion composed of two superposed layers 6 and 7. Between these two layers of the insole is placed a shank stiffener 8. If desirable

this shank stiffener can be almost as wide as the insole. The insole is stitched on either side of the shank stiffener as at 9 to secure this shank stiffener firmly in place and imbed the same in the insole.

This two layer structure of the rear portion of the insole can be provided either by adding one layer to the insole as cut, or by splitting the insole to provide two layers. The layers and stitching together provide a pocket or sleeve in the insole adapted to receive the shank stiffening members. This manipulation of the insole can be conveniently done before assembly of the shoe commences. The assembly follows any of the conventional processes, and the invention can be practiced in relation to a McKay, as well as to a welt. If desirable, a secondary shank stiffener 10 may be used between the outsole and the insole between the inseam lips of the latter as is conventional. This shank stiffener is disclosed as held in position by tacks 11. This structure provides a shoe having a very rigid shank portion as is particularly desirable in a shoe for a heavy person.

The construction herein disclosed is applicable to the outsole in the same manner as disclosed for the insole so that it is optional where it is used. It may be embodied in both soles if desired for double shank strength.

Having described my invention, I claim:

In a shoe, a composite insole composed of a layer of full insole dimension and outline having a marginal inseam lip extending from the underside of the fore part of said layer, a second half length layer for the shank and heel portion of the insole fixed to the underside of said first layer and having marginal lips extending from the underside of the shank portion thereof and continuous with the inseam lip of said first layer, said layers stitched together longitudinally marginally for the shank portion of the insole, and a shank stiffener centrally between said layers secured at its rear end to said second half length layer.

In witness whereof, I hereunto subscribe my name.

JOSEPH BERTRAM. 100
